UNITED STATES PATENT OFFICE.

SOPHIA SWARTZ, OF NEW YORK, N. Y.

COMBINED CHANGE PURSE AND MEMORANDUM BOOK.

Application filed July 18, 1921. Serial No. 485,515.

To all whom it may concern:

Be it known that I, SOPHIA SWARTZ, a citizen of Roumania, residing at New York city, in the county of New York, and State 5 of New York, have invented new and useful Improvements in Combined Change Purses and Memorandum Books, of which the following is a specification.

This invention relates to combined change 10 purse and memorandum book provided with means for securing it to the wrist of the wearer, and the principal object is to provide a simple device of this nature which will provide a suitable receptacle for necessary supplies, will not be burdensome, will 15 be safe, and may be cheaply manufactured.

Another object is to provide a device of this nature in which a pencil may be utilized to lock the edges of the container together. 20

Another object is to provide a device of this nature in which loose-leaf paper may be readily inserted and secured and which shall be made without any metallic fastenings.

With these and other objects in view which will be more apparent as the specification proceeds, the invention resides in certain novel construction and combination and arrangement of parts, the essential features of which are hereinafter fully described, are particularly pointed out in the appended claims, and are illustrated in the accompanying drawing in which:—

Figure 1 is a view of the device closed 35 and suspended from the arm, and

Figure 2 is an open view of my improved device.

Figure 3 is a view showing how the device may be secured against loss by being held 40 directly in contact with the wrist.

Like characters of reference refer to like parts in all views.

Referring to the drawing in detail, 10 represents a piece of flexible material which is 45 bent inwardly at the edges so as to secure in place a lining 11 and a change pocket 12. The device is folded at the middle along the line 13 and a strip of elastic 14 passes both inside and outside of the device along 50 the line 13 and is secured or tacked in place by stitching, gluing or other suitable means at 15 and 16 and the strands of the elastic are secured to each other at 17 forming a loop 18. Two registering loops are provided 55 at the registering edges of member 10 and are indicated by the reference numerals

19 and 20. A pencil 21 is provided which is of sufficient diameter to snugly fit into the loops 19 and 20 and hold the edges securely together when the device is closed. 60 Strips of paper 22 are inserted through under the elastic between the securing points 15 and 16 and held in place by the tension of the elastic band.

It will be seen that in this way I have produced a device in which change and other small articles may be carried and in which they may be securely locked by means of the pencil. 65

In use the wrist of the wearer is inserted 70 in the loop 18 and the distance between 16 and 17 is just sufficient to permit the book to lie flat in the palm of the hand to which the device is secured. In using the book it will be found exceedingly convenient to 75 merely bring the same up into the palm of the hand and then open it with the other hand, the palm of the first hand forming a convenient and effective backing for writing purposes. After the device is locked up it 80 may be allowed to dangle from the wrist as in Figure 2 or may be slipped under the elastic of loop 18 as in Figure 3. In this way should a person desire to play the piano or indulge in any thing else requiring the 85 use of both hands it would not be necessary to lay the purse down where it might be easily forgotten or mislaid or actually stolen and if the purse is placed as shown in Figure 3 there will be no danger from pickpockets and purse snatchers. 90

What is claimed as new is:—

1. A device of the class described comprising a member foldable on itself between its ends and means between the ends of said member and at one side of the line of fold thereof for maintaining strips of flexible material in retained position between the folds of said member, said means having a looped extension projecting from the device 95 at one side of the line of fold thereof and adapted to be engaged with the wrist to permit the device to be extended into the palm of the hand. 100

2. A device of the class described comprising a member foldable on itself between its ends and resilient means between the ends of said member and at one side of the line of fold thereof for maintaining strips of flexible material in retained position between the folds of said member, and a looped portion extending from said member at one 110

side of the line of fold thereof and adapted to engage with the wrist to permit the device to be extended into the palm of the hand.

- 5 3. In a device of the class described, the combination of a body portion, a change pocket secured thereto and a suspension member secured at opposite edges of said body portion so as to form means for maintaining strips of flexible material in position on said body portion, loops secured to the margins of said body portion and means co-operative with said loops for securing said body portion in folded position.
- 10 4. A device of the class described comprising a member foldable on itself between its ends and provided with means located at one side of the line of fold and co-acting with the member to maintain strips of flexible material in retained position between the folds of said member, and a portion extending from said means at a point immediately to one side of the line of fold thereof and adapted to be looped about the wrist of
- 15 20 25 the wearer so that when supported from the wrist, the member may be extended into the palm of the hand.

5. A device of the class described com-

prising a member foldable on itself between its ends and provided with means at one side of the line of fold and co-acting with the member to maintain strips of flexible material in retained position between the folds of said member, a portion extending from said means and adapted to be looped about the wrist of the wearer and operable to respectively permit the member to be suspended from the wrist and held in flat confinement therewith so that when suspended the member may be extended into the palm of the hand.

6. A device of the class described comprising a member foldable on itself between its ends, and means looped cross wise of the member to one side of the line of fold thereof for maintaining strips of flexible material in retained position between the folds of said member, a looped portion extending from the member at one side of the line of fold thereof and adapted to be engaged with the wrist so that the member can be extended into the palm of the hand and means for holding the member closed.

In testimony whereof I have affixed my signature.

SOPHIA SWARTZ.
